COMBINED ELECTRIC AND PNEUMATIC SYSTEM FOR CARS AND THE

1,373,400.

Specification of Letters Patent.

Patented Apr. 5, 1921.

Application filed April 24, 1920. Serial No. 376,316.

To all whom it may concern:

Be it known that we, HERSHEL A. BENEDICT and EDWARD M. MOLLER, citizens of the United States, residing at East Orange, in the county of Essex and State of New Jersey, and Jersey City, county of Hudson, and State of New Jersey, respectively, have invented certain new and useful Improvements in Combined Electric Systems and Pneumatic Systems for Cars and the Like; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements, in railway cars, and especially to improvements in electric street railway cars; and, the present invention has reference, more particularly, to a novel door-operating and controlling mechanism for automatically opening and closing the platform doors of the car, said mechanism being operated by means of the usual air-compressor which is mounted upon the frame-work of the car, and the air from the compressor being under control of the motorman by a foot-operated air valve upon the operating or releasing plunger of which the motorman has his foot, while the car is running.

The present invention, therefore, has for its principal object to provide a novel door-opening and closing means for street railway cars, buses, and the like, which is operated from the air-compressor, as above stated, for stopping the car and opening the platform door or doors, and for closing and locking the door or doors and starting the car, and which door or doors are automatically closed, and must so be closed, before the car can be started.

Other objects of the present invention not at this time more particularly enumerated will be clearly understood from the following detailed description of the present invention.

With the various objects of the present invention in view, the said invention con-

sists, primarily, in a novel control and air-brake system for controlling the movements and locking the platform-door or doors of street-railway cars, buses, and the like; and, the present invention consists, furthermore, in the novel arrangements and combinations of the several devices and parts, all of which will be more particularly set forth in the following specification, and then finally embodied in the clauses of the claims which are appended to and which form an essential part of the said specification.

The invention is clearly illustrated in the accompanying drawings, in which:—

Figure 1 is a control and air-brake diagram for opening and closing the platform-door or doors, of a street-railway car, bus, or the like, said diagrammatical representation of devices and parts illustrating one embodiment of the principles of the present invention.

Fig. 2 is a plan view and Fig. 3 an elevation, looking in the direction of the arrow X in said Fig. 2, of a foot-operated air-valve used with the door-control and air brake system.

Fig. 4 is a diagrammatical representation of the door-operating mechanism or engine, the foot-controlled air-valve, and certain portions of the air-conveying pipes, said view illustrating more particularly the relative positions of the air-ducts within the valve with said pipes, while running the car, and when the door or doors are held in their closed or locked positions; and Fig. 5 is a similar representation of the air-valve, showing the relative positions of the air-ducts within the valve, when the motorman has removed his foot from foot-lever or plunger of the valve, so as to stop the car and simultaneously opening the door or doors.

Similar characters of reference are employed in the said above described views, to indicate corresponding parts.

Referring now more particularly to Fig. 1 of the drawings, in which is shown diagrammatically a general arrangement of electrical instrumentalities for starting and operating the car and a similar arrange-

ment of pneumatic instrumentalities for "braking" the car, and also the novel means for opening and closing the platform door or doors and at the same time controlling the stopping and starting movement of the car, the reference-character 1 indicates the main trolley-wire, with which is in rolling contact any usual construction of trolley-wheel, as 2, carried by the pole 3 with which is connected, in the usual manner, the electric circuit-wire 4. Contained in this circuit, in the usual and well-known manner, are a fuse-box 5, a main switch 6, a line switch 7, a switch-group 8, and the usual electric motor or motors 9, 9. In the accompanying diagram, as represented in said Fig. 1, the system is shown as used with the two platform-ends of a car, so that the car can be operated from either end, and in that case the reference-character 10 indicates a control-switch and 11 a controller upon one platform, and 12 is a control-switch and 13 a controller upon the other platform of the car. Connected with and leading from the circuit-wire 4 is a circuit-wire 14, leading to the control-switch 12, and leading from said control-switch 12 is a circuit-wire 15, in which is placed the previously mentioned controller 13, said circuit-wire 15 being connected with a circuit-wire 16 in which is a control-resistance 17, and which is grounded, as at 18, so as to provide a complete circuit. Also connected with the circuit-wire 4 is a circuit-wire 19 leading to the control-switch 10, and leading from said control-switch 10 is the above-mentioned circuit-wire 16 in which is placed the previously mentioned controller 11, through which the circuit is completed through the control-resistance and the ground 18, as will be clearly understood. Connected with and leading from the circuit-wire 15 is a circuit-wire 20 which terminates in a contact 21, and likewise connected with the control-resistance 17 is a motor-control circuit-wire 22 attached at its opposite end to a contact 23. The reference-character 24 indicates the cylinder of a pneumatic relay in which is disposed a piston or plunger 25 actuated by a spring 26 to cause a member 27 carried by the piston-rod 28 to make contact with the contacts 21 and 23, and thus complete the electrical circuit across said contacts 21 and 23. In connection with the electrical instrumentalities and the electrical circuits herein-above described, we have shown the arrangement of the usual resistance 29, the sequence switch 30, and the reverser 31, as well as the arrangement of the circuit-wire 32 leading from the switch group 8 to the resistance 29, the circuit-wire 33 leading from the switch-group 8 to the sequence-switch 30, and the circuit-wire 34 leading from the switch-group 8 to the reverser 31, the electrical circuit being completed from the circuit-wire 15 with the sequence-switch 30 and the reverser 31 by means of the circuit-wire 35, as indicated in said Fig. 1.

Having in the foregoing in a general manner set forth the general arrangement of the electrical instrumentalities, we will now set forth the general arrangement of the pneumatic instrumentalities and their pipe-connections.

The reference-character 36 indicates an air-compressor provided with an air-intake 37, and electrically operated from the circuit-wire 4, in which is placed a switch 38 and an electric governor 39, a circuit-wire 40 leading to the mechanism of the air-compressor 36, and a leading-out wire 41 which is grounded, as 42, completing the power-serving circuit for the air compressor. Connected with and leading from the air-compressor 36 is a pipe 43 for conveying and forcing the compressed air into the air-receiving tank or reservoir 44. Leading out of said reservoir 44 is a pipe 45 with which is connected the main line of piping 46, termed the reservoir line. The governor 39 is controlled from the air-pressure within the tank or reservoir 44 through a pipe 47, placed between the pipe 45 and the governor 39, as shown.

Connected with the respective ends of the piping 46 are the usual brake-valves, as 48, and 49 indicate air-conveying pipes which are connected with suitably-constructed foot-valves 50, through which the compressed air is adapted to be passed into a line of pipe 51, known as the train line, for actuating the brake-mechanism of the usual brake cylinders 52, connected with said train line by the piping 53. Air gages 54 may be connected with the reservoir line 46 by the pipes 55 in the manner shown.

Connected with and leading from the reservoir line 46 is a pipe 56 which is connected with a control-reservoir 57, and has arranged in said pipe a cut out cock 58. Leading from said control-reservoir 57 is a pipe 59, in which may be placed a strainer 60, for conveying the compressed air to the mechanism of the reverser 31. Furthermore, there is connected with said pipe 59 another pipe 61 for conveying the compressed air to the mechanism of the switch group 8 and the line switch 7, in a manner as indicated in said Fig. 1. To pneumatically operate the piston or plunger 25 of the hereinbefore mentioned pneumatic relay, so as to break the electrical circuit between the contacts 21 and 23 and the member 27 carried by the piston rod 28, an air-conveying pipe 62 is disposed between the train line 51 and the end of the cylinder 24 of the pneumatic relay, as shown.

Referring now more particularly to Figs. 2 to 5 inclusive, each previously mentioned foot-valve 50 comprises a suitably formed

shell or casing, as 63, in the cylindrically formed valve-chamber of which is oscillatorily disposed a valve-disk or member, as 64, mounted upon a spindle 65 having its respective ends journaled in suitably formed bearing-positions or members 66. Pipes 67 also connect the reservoir line 46 with an inlet to each shell or casing 63, for the purpose to be presently set forth. As indicated in the diagrammatic views represented in said Figs. 4 and 5 of the drawings, the fixed or stationary portion of each shell or casing 63 is provided with an arrangement of ducts, as 68, 69, 70, 71, 72 and 73, the pipe 67 being connected with the duct 68, pipe 49 with the duct 69, and pipe 51 with the duct 70. Similarly the duct 71 connects with a pipe 74, duct 72 with a pipe 75, and duct 73 with a pipe 76, all for the purposes to be presently more fully described. In communication with the respective stationary or fixed ducts 68, 69, 70, 71, 72 and 73, are connecting duct-portions 77, 78, 79, 80, 81 and 82, said duct-portion being adapted to establish communication with ducts 83, 84 and 85 in the valve-disk 64 in either of the manners represented in said Figs. 4 and 5 of the drawings.

One means of oscillating the valve-disk 64, so as to establish communication between the respective ducts, as shown in said Fig. 4, or in said Fig. 5, is by means of a foot-lever or pedal, as 86, which is mounted as at 87, upon a pivot-pin 88, extending across a portion 89 of the shell or casing 63. The said portion is also provided with a pin or stud 90, and attached to that part of said stud within said portion 89 is one end of a spring 91, said spring being also attached at its other end to the part 87 of the foot-lever or pedal 86. Pivots connected with a portion 92 of said lever or pedal 86, which is movably disposed in an opening, as 100, in said portion 89, by means of a pintle 93, is a link 94, said link being operatively connected at its end-portion 95 with a connection 96, disposed between a bifurcated end-portion 98 of a suitably formed crank, as 97, said crank being suitably connected by means of a socket-portion 99 with the end of the spindle 65. From an inspection of said Figs. 5 and 6 it will be seen, that the reciprocatory movements of the foot-lever or pedal vertically, by means of the above described elements, are transformed into reciprocatory movements horizontally of the crank 97, so that the downward position of the lever or pedal 86, when depressed by the foot of the motorman, causes the valve-disk 64 and the various ducts to assume the relative positions indicated in Fig. 4 of the drawings; but when the foot-pressure is removed from the lever or pedal 86, the spring 91 causes the lever or pedal to assume the dotted position indicated in Fig. 3, and thus

causes the valve-disk 64 and the various ducts to assume the relative positions, as represented in Fig. 5 of the drawings.

The door-operating mechanism for pneumatically opening and closing the platform doors of the car is diagrammatically illustrated in Figs. 1 and 4 of the drawings, and one embodiment of the same is an arrangement of four cylinders 101, 102, 103 and 104, respectively provided with pistons or plungers 105, 106, 107 and 108. As shown, these cylinders are arranged in pairs, the cylinder 101 being opposite the cylinder 102, and the cylinder 103, being opposite the cylinder 104. The pistons 105 and 106 are interconnected by a connecting rod 109 provided with a rack-portion 110, and the pistons 107 and 108 are likewise interconnected by a connecting rod 111, also provided with a rack-portion 112 being in mesh with the teeth of a pinion 113 forming part of the mechanism for actuating the link-connections 114, or other mechanism for opening and closing the usual car-door 115.

Having in the foregoing description set forth the general arrangements and combinations of devices and parts for locking the doors in their closed relation before the car or bus can be operated, and after the doors have closed permitting the operation of the car; and, furthermore, for opening the doors automatically after the car has been started, we will now briefly set forth the manner of producing these results.

Let us suppose that the car is about to be started and that the doors are in their open positions.

The motorman, just prior to operating the respective controller 11 or 13, so as to turn on the electric current, depresses the foot-lever or pedal 86 of the corresponding foot-valve 50. Immediately the valve-disk 64 is brought into the position, indicated in Fig. 4, and the compressed air passes from the tank or reservoir 44 through the pipe 45 into the reservoir line or pipe 46, and thence by means of the pipe through the registering ducts 68, 77, 83, 81 and 72 into and through the piping 75, and thence into the ends of the cylinders 101 and 104, so that the pistons 105 and 108 are moved forward into the positions shown in said Fig. 4, whereby the doors are positively closed, the previously intaken air in the cylinders 102 and 103 being exhausted through the piping 74, the registering ducts 71, 80, 85, 82 and 73, into and from the exhaust pipe 76. At the same time, the motorman by operating and closing the brake-valve 48 shuts off the air pressure through the pipes 49 and 51, thus removing any air-pressure against the piston 25 in the relay-cylinder 24, whereupon the spring 26 become active, and an electrical contact is established between the bar or member 27 and the contacts 21 and 23. An

uninterrupted electric circuit thus being established and the car is electrically propelled, in the usual manner.

- When it is desired to stop the car, the 5 brake-valve 48 is opened so that the compressed air from the line of piping 46 will pass through said valve 48, into the pipe 49 and through the registering ducts 69, 78, 84, 79 and 70, see Fig. 4, into the train line or 10 piping 51, and by means of the pipe 53 actuating the piston in the brake-cylinder 52, so as to set the brakes, the air-pressure at the same time, by means of the pipe 62 actuating the relay-piston 25, so as to break the 15 electrical circuit through the bar or member 27 and the contacts 21 and 23, and thus shutting off the electricity to the propelling or driving mechanism of the car, as will be understood.
- 20 The car now having been stopped, the motorman removes his foot from the foot-lever or pedal 86, whereupon the spring moves the pedal into the dotted position shown in said Fig. 3, and whereby the valve 25 disk 64 is rotated into the position indicated in Fig. 5 of the drawings.

The compressed air coming through the reservoir line or pipe 46 and the pipe 67 passes through the registering ducts 68, 77, 30 83, 80 and 71, into the piping 74 and thence into the cylinders 102 and 103, against the pistons 106 and 107, driving the latter forwardly to actuate the door-operating mechanism and thereby moving the doors into 35 their opened positions. Simultaneously the air contained in the cylinders 101 and 104 is caused by the moving pistons 105 and 108 to be exhausted through the piping 75, and the registering ducts 72, 81, 85, 82 and 40 73 into and from the exhaust pipe 76.

While the car is stopped, that the air is not shut off from the brake-cylinder 52 and the relay-cylinder 24, communication between the pipes 46 and 67 and 51 is also established through the registering ducts 68, 45 77, 83, 79 and 70, as will be seen from an inspection of Fig. 5 of the drawings.

To again close the doors and to start the car, the first above stated operation of closing the brake valve 48 and depressing the foot-lever or pedal 86, so as to bring the valve-device 64 once more into the position indicated in Fig. 4 of the drawings, are repeated.

55 Of course we are fully aware, that changes may be made in the general arrangements and combinations of the various devices and parts, and especially in the details of the construction of the said parts, without departing from the scope of the present invention as set forth in the foregoing specification, and as defined in the clauses of the claims which are appended to the said specification. Hence, we do not limit our invention to the exact arrangements and combina-

tions of the various devices and parts, as described in the said specification, nor do we confine ourselves to the exact details of the construction of the said parts, as illustrated in the accompanying drawings.

70

We claim:—

1. In combination with an electric system for operating cars, or the like, a make and break means in said system, a pneumatic system for actuating said make and break 75 means, and a pneumatically controlled door-operating mechanism connected and coöperating with said pneumatic system, primarily for maintaining a locked arrangement of the car-door or doors while the car 80 is running, and secondarily for opening the car-door or doors when the car has stopped.

2. In combination with an electric system for operating cars, or the like, a make and break means in said system, a pneumatic 85 system for actuating said make and break means, a pneumatically controlled door-operating mechanism, and a valve located in said pneumatic system for directing the flow of the air in said pneumatic 90 system, primarily for maintaining a locked arrangement of the car-door or doors while the car is running, and secondarily for opening the car-door or doors when the car has stopped.

95 3. In combination with an electric system for operating cars, or the like, a make and break means in said system, a pneumatic system for actuating said make and break means, a pneumatically controlled door-operating mechanism, and a foot-operated rotary valve located in said pneumatic system for directing the flow of the air in said pneumatic system, primarily for maintaining 100 a locked arrangement of the car-door or doors while the car is running, and secondarily for opening the car-door or doors when the car has stopped.

105 4. In combination with an electric system for operating cars, or the like, a make and break means in said system comprising a cylinder, a spring-controlled piston within said cylinder, a pneumatic system for actuating said piston, said pneumatic system comprising an air-compressor and an air-receiving reservoir, a reservoir line connected with said reservoir, a train-line leading to and connected with said cylinder, a control-valve with which said reservoir and train lines are connected, a door-operating mechanism, and an air-conveying means between said control-valve and the said door-operating mechanism.

115 5. In combination with an electric system for operating cars, or the like, a make 125 and break means in said system comprising a cylinder, a spring-controlled piston within said cylinder, a pneumatic system for actuating said piston, said pneumatic system comprising an air-compressor and an air- 130

receiving reservoir, a reservoir line connected with said reservoir, a train-line leading to and connected with said cylinder, a control-valve with which said reservoir and 5 train lines are connected, a door-operating mechanism, comprising a plurality of cylinders arranged in pairs, the pistons of each pair of cylinders being interconnected by a single connecting rod, means actuated from 10 said rods for operating the doors of the car, and air-conveying pipes leading from said control-valve and connected with the respective cylinders for actuating said pistons.

6. In combination with an electric system 15 for operating cars, or the like, a make and break means in said system comprising a cylinder, a spring-controlled piston within said cylinder, a pneumatic system for actuating said piston, said pneumatic system 20 comprising an air-compressor and an air-receiving reservoir, a reservoir line connected with said reservoir, a train-line leading to, and connected with said cylinder, a control-valve with which said reservoir and 25 train lines are connected, comprising a valve-casing, a rotary valve-disk within said casing, a foot-lever for operating said valve-disk, a door-operating mechanism, and an air-conveying means between the casing of 30 said control-valve and the said door-operating mechanism, said valve-disk being provided with a plurality of ducts adapted to establish communication with said reservoir and train lines and also with the air- 35 conveying means of said door-operating mechanism.

7. In combination with an electric system 40 for operating cars, or the like, a make and break means in said system comprising a cylinder, a spring-controlled piston within said cylinder, a pneumatic system for actuating said piston, said pneumatic system comprising an air-compressor and an air-receiving reservoir, a reservoir line connected 45 with said reservoir, a train-line leading to and connected with said cylinder, a control-valve with which said reservoir and train-lines are connected, comprising a valve-casing, a rotary valve-disk within 50 said casing, a foot-lever for operating said valve-disk, a door-operating mechanism, comprising a plurality of cylinders arranged in pairs, the pistons of each pair of cylinders being interconnected by a single connecting rod, means actuated from said rods 55 for operating the doors of the car, and air-conveying pipes leading from said control-valve and connected with the respective cylinders for actuating said pistons; said valve- 60 disks being provided with a plurality of ducts adapted to establish communication with said reservoir and train-lines and also with the air-conveying pipes leading from said control-valve to the cylinders of said 65 door-operating mechanism.

8. In combination with an electric system 70 for operating cars, or the like, a make and break means in said system comprising a cylinder, a spring-controlled piston within said cylinder, a pneumatic system for actuating said piston, said pneumatic system comprising an air-compressor and an air-receiving reservoir, a reservoir line connected with and leading from said reservoir, a train-line leading to and connected with said cylinder, a brake-valve mechanism connected with said reservoir line, an air-conveying means leading from said brake-valve mechanism, a control-valve with which said air-conveying means and the said train-line 75 are connected, a door-operating mechanism, and an air-conveying means between said control-valve and the said door-operating mechanism.

9. In combination with an electric system 80 for operating cars, or the like, a make and break means in said system comprising a cylinder, a spring-controlled piston within said cylinder, a pneumatic system for actuating said piston, said pneumatic system 85 comprising an air-compressor and an air-receiving reservoir, a reservoir line connected with and leading from said reservoir, a train-line leading to and connected with said cylinder, a brake-valve mechanism connected with said reservoir line, an air-conveying means leading from said brake-valve 90 mechanism, a control-valve with which said air-conveying means and the said train-line are connected, a door-operating mechanism, comprising a plurality of cylinders arranged in pairs, the pistons of each pair of cylinders being interconnected by a single connecting rod, means actuated from said rod for operating the doors of the car, and air-conveying pipes leading from said control-valve and connected with the respective cylinders for actuating said pistons.

10. In combination with an electric system 100 for operating cars, or the like, a make and break means in said system comprising a cylinder, a spring-controlled piston within said cylinder, a pneumatic system for actuating said piston, said pneumatic system 105 comprising an air-compressor and an air-receiving reservoir, a reservoir line connected with and leading from said reservoir, a train line leading to and connected with said reservoir line, an air-conveying means 110 leading from said brake-valve mechanism, a control-valve with which said air-conveying means and the said train-line are connected, comprising a valve-casing, a rotary valve-disk within said casing, a foot-lever for 115 operating said valve-disk, a door-operating mechanism, and an air-conveying means between said control-valve and the said door-operating mechanism, said valve-disk being provided with a plurality of ducts adapted 120 to establish communication with the air-con- 125

- veying means leading from said brake-valve mechanism, and with said train line, and also with the air-conveying means of said door-operating mechanism.
- 5 11. In combination with an electric system for operating cars, or the like, a make and break means in said system comprising a cylinder, a spring-controlled piston within said cylinder, a pneumatic system for actuating said piston, said pneumatic system comprising an air-compressor and an air-receiving reservoir, a reservoir line connected with and leading from said reservoir, a train line leading to and connected with said cylinder, a brake-valve mechanism connected with said reservoir line, an air-conveying means leading from said brake-valve mechanism, a control-valve with which said air-conveying means and the said train-line 10 are connected, comprising a valve-casing, a rotary valve-disk within said casing, a foot-lever for operating said valve-disk, a door-operating mechanism, comprising a plurality of cylinders arranged in pairs, the pistons of each pair of cylinders being interconnected by a single connecting rod, means actuated from said rods for operating the doors of the car, and air-conveying pipes leading from said control-valve and connected with the respective cylinders for actuating the pistons of said cylinders.
- 15 12. In combination with the air-brake control of a car, a door-operating mechanism, 40 a foot-operated control valve comprising a part of and connected with said air-brake control, a door-operating mechanism, and an air-conveying means between said control-valve and said door-operating mechanism for actuating the same. 45
13. In combination with the air-brake control of a car, a door-operating mechanism, a valve-casing, a rotary valve-disk within said casing, a foot-lever for operating said 50 valve disk, a door-operating mechanism, and means between the casing of said control-valve and the said door-operating mechanism for actuating the same.
14. In combination with the air-brake control of a car, a door-operating mechanism, a valve-casing, a rotary valve-disk within said casing, a foot-lever for operating said 55 valve-disk, a door-operating mechanism, comprising a plurality of cylinders arranged 60 in pairs, the pistons of each pair of cylinders being inter-connected by a single connecting rod, means actuated from said rods for operating the doors of the car, and air-conveying pipes leading from said control-valve and 65 connected with the respective cylinders for actuating the pistons of said cylinders.
- In testimony, that we claim the invention set forth above we have hereunto set our hands this 10th day of April, 1920.
